UNITED STATES PATENT OFFICE.

MILTON H. KNAPP, OF SAGINAW, MICHIGAN.

ATTACHMENT FOR DENTAL ARTICULATORS.

No. 856,884.

Specification of Letters Patent.

Patented June 11, 1907.

Application filed August 16, 1906. Serial No. 330,846.

To all whom it may concern:

Be it known that I, MILTON H. KNAPP, a citizen of the United States, residing at Saginaw, in the county of Saginaw and State of Michigan, have invented certain new and useful Improvements in Attachments for Dental Articulators; and I do hereby declare the following to be a full, clear, and exact description of the invention, such as will enable others skilled in the art to which it appertains to make and use the same.

My invention relates to attachments for dental articulators and is applicable to the usual articulators in common use, the object being to provide a wide range of adjustment to correct imperfect "bites" and obtain a perfect articulation between the natural and artificial teeth, in other words, to obtain an exact "anatomical" adjustment.

In the accompanying drawings, Figure 1 is a perspective view of an articulator equipped with my invention; Fig. 2 is a top plan view of the attachment alone; and Fig. 3 is a detail side view of the attachment disassembled.

Articulators comprise a lower jaw (1), an upper support (2) pivotally connected thereto, as at (3) and an adjusting screw (4) carried by the lower jaw and engaging the support.

My attachment comprises a plate (5) slotted as at (6) to receive a set screw (7') taking into the upper support.

A pair of oppositely located slotted ears (7) (7) are secured to the outer end of the plate (5) and extend transversely thereof, the plate adjacent the ears being recessed, as at (8) (8) to receive the apertured lugs (9)

(9) projecting rearwardly from the upper jaw section (10). The lugs are preferably spaced a less distance apart than are the ears 40 and are received in the recesses (8) (8) between the ears, the recesses permitting a vertical linear, as well as a vertical swinging adjustment of the lugs relative to the ears. Set screws (11) (11) pass through the slots in the 45 ears and are received in the apertures of the lugs.

Having thus fully disclosed my invention, what I claim as new is—

1. The combination with a dental articulator, of a slotted plate secured thereto, slotted ears located at the outer end of the plate, an upper jaw section, apertured lugs carried by the section, and fastening means for connecting the lugs and ears, to permit vertical 55 linear and swinging adjustments of the sections relative to the plate.

2. An attachment for dental articulators comprising a plate and an upper jaw section loosely connected to the plate to permit a 60 vertical adjustment of the jaw section independently of the plate.

3. The combination with a dental articulator, of a suitably supported plate, and an upper jaw section pivotally and vertically 65 adjustable relative to and independently of the plate.

In testimony whereof, I affix my signature in presence of two witnesses.

MILTON H. KNAPP.
